UNITED STATES PATENT OFFICE

173,109

HAT OR THE LIKE

Harvey Hill, Akron, Ohio

Application May 18, 1954, Serial No. 30,547

Term of patent 7 years

(Cl. D3—13)

To all whom it may concern:

Be it known that I Harvey Hill, a citizen of the United States, residing at Akron, in the county of Summit and State of Ohio, have invented a new, original, and ornamental Design for a Hat or the like, of which the following is a specification, reference being had to the accompanying drawing, forming a part hereof.

Figure 1 is a side perspective view of a hat showing my new design; and

Figure 2 is a top plan view thereof.

I claim:

The ornamental design for a hat or the like, as shown.
